DELIVERY SYSTEM

Stephen L. Fitzpatrick, Detroit, Mich.

Application April 21, 1948, Serial No. 22,386

10 Claims. (Cl. 302—36)

1

This invention relates broadly to fuel-delivery systems; more particularly, the invention relates to a novel tank for storing powdered solid fuel such as coal and the like and to means for delivering fuel at a controlled rate from the tank.

An important object of the present invention is to provide an apparatus for storing powdered coal and the like in a clean, efficient and convenient manner.

Another object of the invention is to provide an apparatus of the above-mentioned character having a storage tank and a fuel-delivery system associated with the storage tank, which system is uniquely adapted to remove fuel rapidly at a controlled rate from the tank.

Still another object of the invention is to provide a storage tank of the above-mentioned character that is adapted either for delivery trucks or for stationary installations.

Yet another object of the invention is to provide an apparatus of the above-mentioned character wherein the delivery system is uniquely constructed to prevent lumping or caking of the fuel.

A further object of the invention is to provide a delivery system of the above-mentioned character having novel means for preventing the fuel from accumulating at the sides of the tank.

A still further object of the invention is to provide a delivery system of the above-mentioned character having means for promoting easy flow of fuel downwardly in the tank.

Still another object of the invention is to provide a delivery system of the above-mentioned character having a screw conveyer for delivering fuel from the tank and a novel means for increasing the discharge capacity of the apparatus, which means can be employed to supplement or, if desired, substitute for the main screw conveyer.

Other objects and advantages of the invention will be apparent during the course of the following description.

In the drawings forming a part of this specification and wherein like numerals are employed to designate like parts throughout the same:

Fig. 1 is a side elevation of a storage tank and associated delivery system embodying the invention, parts of the apparatus being broken away and shown in section for clearness of illustration;

Fig. 2 is a transverse, vertical sectional view taken on the line 2—2 of Fig. 1;

Fig. 3 is a transverse, vertical sectional view taken on the line 3—3 of Fig. 1;

2

Fig. 4 is a fragmentary, horizontal, longitudinal sectional view taken on the line 4—4 of Fig. 1; and

Fig. 5 is a transverse, vertical sectional view taken on the line 5—5 of Fig. 1.

In the drawings, wherein, for the purpose of illustration, is shown a preferred embodiment of the invention, the numeral 10 designates a storage tank for powdered solid fuel such as coal or the like. The tank 10 preferably is constructed of sheet metal and is held in an elevated position by a suitable supporting structure 12. The tank 10 may or may not be divided into separate compartments; however, the tank shown by the drawings is provided with transverse partitions 14 which divide the same into three separate compartments. Each compartment may be filled independently of the others through openings in the top of the tank. These top openings are closed and sealed by suitable covers 16; and if the tank 10 is relatively large, the top openings preferably are sufficiently large to admit a workman to enter the various compartments to clean or repair the equipment.

25 Powdered fuel is delivered to the various compartments of the tank 10 through pipes 18 which connect and open through the covers 16. As fuel accumulates in the tank 10, air is exhausted to the atmosphere through the pipe 20. Preferably a precipitator 22 of the type shown in my copending application Serial No. 30,080 which was filed on the 29th day of May 1948, is provided at the discharge end of the exhaust pipe 20 to collect and return to the tank any fuel which may be carried out of the tank with the escaping air.

30 The bottom of the tank 10 may be flat or inclined; however, the tank here shown is provided with an essentially flat, horizontal bottom 24, and the latter is formed with a relatively shallow, longitudinal trough 26 which preferably extends the full length of the tank. Powdered fuel fills the trough 26 and, when desired, is moved longitudinally to discharge openings 28 at one end 42 of the tank by a pair of parallel screw conveyers 30 and 32. The screw conveyers 30 and 32 preferably extend the full length of the trough 26, and they are supported for rotation adjacent their ends by suitable bearings 34 and 36. In this connection the supporting bearings 34 are disposed in the tank 10 and adjacent the end wall 38 thereof. However, the opposite ends of the screw conveyers 30 and 32 extend through the discharge openings 28, through the 35 housing of a blower 40 which is mounted exte-

riorly of the housing adjacent the end 41 thereof, and into a gear housing 42 where they are drivingly connected to a motor 66 or the like in a manner hereinafter described in detail. The supporting bearings 36 are here shown mounted on a portion 44 of the gear housing 42.

Specifically the drive for the screw conveyers 30 and 32 comprises gears 46 and 48 (Fig. 3) which are mounted on the ends of the conveyers within the gear housing 42. Gears 46 and 48 mesh with idler gears 50 and 52 respectively, the latter gears are keyed or otherwise fastened to respective shafts 54 and 56 which are suitably journaled in the gear housing 42, and these shafts also carry gears 58 and 60 which mesh with a single gear 62 which is fast on the drive shaft 64 of driving motor 66. Thus the screw conveyers 30 and 32 are rotatably driven simultaneously in the same direction, as indicated by the arrows in Fig. 3 to move powdered fuel in the tank 10 to the two discharge openings 28. Manifestly the rate of movement of the fuel will be relatively uniform, and the amount of fuel delivered per unit of time can be easily controlled by regulating the rotative speed of the screw conveyers.

Since the blower 40 is mounted between the tank 10 and the motor 66, the drive shaft 64 of the motor conveniently can be extended entirely through the gear housing 42 into the blower housing and connected to the blower fan. Thus the single motor 66 can be utilized to drive the screw conveyers 30 and 32 and also to drive the blower fan. The blower 40 is mounted so that it discharges a direct down blast at the end of the tank 10, and the forced draft of air generated by the blower is conducted downwardly through a vertical air duct 68.

The portions of the screw conveyers 30 and 32 which extend through the blower housing 40 are enclosed in separate, generally tubular casings 70 and 72 (Fig. 2). These casings extend horizontally entirely through the blower housing and receive fuel which is moved from the tank 10 by the conveyers 30 and 32. At substantially the middle thereof, the casings 70 and 72 are provided with depending fuel-discharge pipes 74 and 76 respectively which extend downwardly and carry the fuel into the air duct 68. Each of the pipes 74 and 76 makes a smooth, ninety-degree bend at the bottom thereof so that the fuel discharges horizontally therefrom. The air duct 68 also makes a ninety-degree turn with the pipes 74 and 76, and the horizontally extending portion 78 of the duct preferably is of reduced diameter and forms a relatively long feed line to the furnace or other point of destination. If the apparatus is adapted to deliver fuel to a furnace, a delivery tank 79 for a fuel carburetor of the type shown in my copending application Serial No. 30,080 which was filed on the 29th day of May, 1948, may be inserted in the line 78 ahead of the furnace to assure a uniform feed and to disseminate the fuel evenly in the current of air which carries it to the furnace.

In this connection it will be observed that the horizontally directed outlets of discharge pipes 74 and 76 register substantially with the horizontal feed-line portion 78 of the air duct 68 so that coal discharged from the pipes flows smoothly into the feed line. Also, it will be apparent that the forced downdraft of air created in duct 68 by blower 40 creates a suction in the discharge pipes 74 and 76 which assists in drawing the coal at a substantially even rate from the pipes. The air is supplied to the duct 76 in suffi-

cient volume so that all the coal discharged from the tubes 74 and 76 is picked up instantly and carried along into the feed line 78.

Just above the elbows of the discharge pipes 74 and 76 and on the opposite sides from the discharge openings of the pipes are horizontal slits 80 and 82 through which air passes into the lower portions of the pipes. Also, it will be observed that the discharge pipes 74 and 76 are formed to catch part of the air flowing downwardly through the air duct 68 and to direct the same through the slits 80 and 82 into the fuel-discharge pipes 74 and 76. Air entering through slits 80 and 82 sweeps through the lower portions of the pipes 74 and 76, prevents coal from settling and accumulating at the bottom of the elbows, and forces the coal out into the feed line 78. However, the bulk of the air generated by blower 40 flows outside the fuel-discharge pipes 74 and 76, and, as suggested, as the air passes the outlet of the pipes 74 and 76, the air draws along the fuel with it by its induction effect.

In order to increase the capacity of the fuel-delivery system, I provide separate horizontal ducts 84 and 86 under the trough 26 and immediately below respective screw conveyers 30 and 32. Openings 88 controlled by gate valves 90 are provided at spaced points along the bottom of trough 26, and these openings effect communication between the latter and the ducts 84 and 86. Valves 90 are operated in unison by a connecting rod 91, which rod extends exteriorly of the tank 10 and is provided with a manually operable handle 92. When the valves 90 are open, powdered fuel in the trough 26 falls downwardly into the ducts 84 and 86 continuously during operation of the screw conveyers 30 and 32. As the screw conveyers operate, they turn and agitate the fuel in the trough 26; and since the screw conveyers are rotated simultaneously at the same speed, they supply coal at a fairly uniform rate to both ducts 84 and 86.

An elbow or nozzle 94 extends downwardly from each opening 88. These nozzles 94 extend into the ducts 84 and 86, and the lower ends thereof are directed horizontally toward the end 42 of the tank 10. Thus the nozzles 94 deliver fuel horizontally into the ducts 84 and 86 and in the direction of the air duct 68. In this connection it will be observed (Fig. 1) that the ducts 84 and 86 open into the air duct 68 at 95 so that fuel is delivered into the duct 68 from the ducts 84 and 86. This coal is carried downwardly in duct 68 by the air flowing therethrough; and as the mixture of air and coal enters the feed line 78, it merges with the coal coming from the discharge pipes 74 and 76.

In order to assist movement of the coal longitudinally in ducts 84 and 86, I provide air tubes 96 and 98 which extend from and communicate with the duct 68. As shown in Fig. 2, the air tubes 96 and 98 extend rearwardly alongside the fuel ducts 84 and 86 and connect with the ducts adjacent the rearward ends thereof, as shown in Fig. 1. Air from the duct 68 is carried to the rearward ends of fuel ducts 84 and 86 through air tubes 96 and 98; and as this air moves forwardly through the ducts 84 and 86, it carries coal in the latter to the duct 68. Air flowing downwardly in duct 68 past the openings 95 creates a suction in the ducts 84 and 86 which generates a natural flow of air through the ducts 84 and 86 and assists in moving the coal into the air duct 68.

In order to start air moving through the ducts

84 and 86 when operation of the system is first begun or if required during operation thereof, I provide each of the nozzles 94 with a jacket 99 and deliver air under pressure to the jackets behind the discharge openings of the nozzles. In Fig. 1 I have shown a tank 100 of compressed air mounted on the supporting structure 12. Air under pressure from the tank 100 passes through a pipe 102 into a manifold 104 and thence through branch pipes 106 to the jackets 99. Each branch pipe 106 is controlled by a manually operated valve 108. Also, air from pipe 102 may enter the feed line 78 through a second pipe 110 to assist in moving the fuel through the line 78 when the operation of the system is first begun or as required during operation of the same. Pipe 110 is controlled by a manually operated valve 112 so that air from the tank 100 can be cut off or admitted to the feed line at a controlled rate. If desired, air under pressure may be supplied continuously to the tank 110 by an air compressor or the like (not shown) during operation of the system. Air supplied to the jackets 99 discharges forwardly into the ducts 84 and 86 past the discharge orifices of nozzles 94, and air flowing past the orifices induces a flow of fuel through the nozzles and carries the fuel discharged from the nozzles longitudinally through the ducts 84 and 86 into the air duct 68 and thence to the supply line 78.

Fuel in the tank 10 tends to funnel into the trough 26; and in order to move the fuel which accumulates on the bottom 24 at opposite sides of the trough, I provided a pair of manually operable scrapers 120. The scrapers 120 extend the full length of the tank 10 through suitable openings 122 (Fig. 5) in the partitions 14 so that each scraper operates to move fuel in all three compartments of the tank simultaneously to the trough 26. The scrapers 120 may be operated at any time during operation of the apparatus; however, it usually is necessary to operate them only when the supply of fuel in the tank 10 is relatively depleted.

Specifically, each of the scrapers 120 comprises a pair of shafts 124 and 126 which are supported in laterally spaced, parallel relation above the bottom 24 by supports 128. Laterally aligned pairs of driving sprockets 130 and 132 are fixed on the shafts 124 and 126, and an endless chain 134 is trained over each pair of sprockets. Radially projecting scraper blades 136 carried by the endless chains 134 extend the full length of the tank 10. By rotating the chains simultaneously in the direction of the arrow in Fig. 5, the blades 136 are caused to move across the floor of the tank to move fuel into the trough 26.

Any suitable, manually or mechanically operable driving means may be provided for the scrapers 120. In the form of the invention here shown by way of illustration, I provide a manually operable drive for each scraper.

In each instance, the shaft 124 is a driving shaft, and the shaft 126 is an idler shaft which is driven only through the sprockets 130 and 132 and endless chains 134. As shown in Fig. 4, the drive shaft 124 projects through the rearward end 38 of the tank 10, and the projecting end thereof carries a gear 140 which is keyed or otherwise rotatably fixed thereto. The gear 140 meshes with a gear 142 which is suitably journaled on the housing 10, and the latter gear carries a companion gear 144 which rotates therewith and meshes with a gear 146. A manually operable hand wheel 148 is provided to rotate

the latter gear, and all of the gearing is enclosed in a suitable housing 150.

Thus to drive the scrapers 120 it is merely necessary to rotate the hand wheel 148, and the latter act through the gear drives to actuate the scraper mechanisms. In the form of the invention here shown, the two scrapers 120 are separately operable.

It is to be understood that the form of the invention herewith shown and described is to be taken as a preferred example of the same and that various changes in the size, shape, and arrangement of parts may be resorted to without departing from the spirit of the invention or the scope of the appended claims.

Having thus described the invention, I claim:

1. In apparatus of the character described, a storage receptacle for powdered fuel, said receptacle having a bottom, a longitudinal passage below said bottom and openings in said bottom through which fuel passes from the receptacle into the passage; a discharge duct at one end of said passage; nozzles extending into the passage from said openings, said nozzles having outlets facing the discharge ducts and adapted to deliver fuel from said openings horizontally into said passage; jackets around and spaced from said nozzles, said jackets having discharge openings disposed in register with the outlets in said nozzles; and means for delivering air under pressure to the jackets behind said discharge openings.

2. In apparatus of the character described, a storage receptacle for powdered fuel, said receptacle having a bottom, a discharge opening at one end thereof immediately above said bottom, a longitudinal passage below said bottom, and openings in said bottom through which fuel passes from the receptacle into the passage; means including a screw conveyer in said receptacle for delivering fuel to said discharge opening and for agitating the fuel above said bottom openings; nozzles extending into said passage from said bottom openings, said nozzles having outlets facing one end of the passage and adapted to deliver fuel from said bottom openings horizontally into said passage; and means for creating a suction in the outlets of said nozzles.

3. The combination as set forth in claim 2 including means within said receptacle for delivering fuel to said screw conveyer.

4. The combination as set forth in claim 2 including manually operable means on the bottom of said receptacle at opposite sides of said screw conveyer for moving fuel to said conveyer.

5. A delivery system for powdered fuels comprising a storage receptacle for powdered fuel having a bottom therein, a vertical discharge duct at the end of said receptacle extending downwardly from said bottom and provided at the lower end thereof with a horizontal extension, a longitudinal trough in said bottom opening into said duct, screw conveyer means in said trough for moving said fuel into said duct, a pipe in and of smaller diameter than the duct for receiving fuel delivered to the duct by said conveyer means, said pipe extending downwardly to substantially the bottom of the duct, an elbow on the lower end of the pipe having a discharge opening arranged to deliver fuel substantially horizontally into the extension of said duct, means for forcing a current of air under pressure downwardly through the duct around said pipe and past the discharge opening of said elbow, and an upwardly opening transversely elongated slit in the back of said

elbow for by-passing part of said air into the elbow, said slit having spaced walls for guiding and directing by-passed air downwardly into the elbow and terminating behind said discharge opening whereby the by-passed air sweeps over the bottom of the elbow and prevents fuel particles from accumulating thereon, and whereby outside air flowing past the outlet of the nozzle has an induction effect tending to draw fuel from the nozzle.

6. A delivery system for powdered fuels comprising a storage receptacle for powdered fuel having a bottom therein, a vertical discharge duct at the end of said receptacle extending downwardly from said bottom and provided at the lower end thereof with a horizontal extension, a longitudinal trough in said bottom opening into said duct, a longitudinal passage below said trough opening at one end into said duct, and openings interconnecting the trough and said passage through which fuel passes from the trough into the passage, screw conveyer means in said trough for moving fuel into said duct and for agitating fuel in the trough to promote flow of fuel through said openings into said passage, a pipe in and of smaller diameter than the duct for receiving fuel delivered to the duct by said conveyer, said pipe extending downwardly to substantially the bottom of the duct, an elbow on the lower end of the pipe having a discharge opening arranged to deliver fuel substantially horizontally into the extension of said duct, means for forcing a current of air under pressure downwardly through the duct around said pipe and past the discharge opening of said elbow and also longitudinally through said passage to move fuel delivered thereto through said openings into the duct, and an upwardly opening slit in the back of said elbow for by-passing part of the air traversing said duct into the elbow, said slit having spaced front and rear walls for guiding and directing by-passed air downwardly into the elbow and terminating behind said discharge opening, whereby the by-passed air sweeps over the bottom of the elbow and prevents fuel particles from accumulating thereon and whereby outside air flowing past the outlet of the nozzle has an induction effect tending to draw fuel from the nozzle.

7. A delivery system for powdered fuels comprising a storage receptacle for powdered fuel having a bottom therein, a vertical discharge duct at the end of said receptacle extending downwardly from said bottom and provided at the lower end thereof with a horizontal extension, a longitudinal trough in said bottom opening into said duct, a longitudinal passage below said trough opening at one end into said duct, and openings interconnecting the trough and said passage through which fuel passes from the trough into the passage, screw conveyer means in said trough for moving fuel into said duct and for agitating fuel in the trough to promote flow of fuel through said openings into said passage, a pipe in and of smaller diameter than the duct for receiving fuel delivered to the duct by said conveyer, said pipe extending downwardly to substantially the bottom of the duct, an elbow on the lower end of the pipe having a discharge opening arranged to deliver fuel substantially horizontally into the extension of said duct, means for forcing a current of air under pressure downwardly through the duct around said pipe and past the discharge opening of said elbow, separate means for creating a forced draft

of air longitudinally through said passage in the direction of said duct, said air picking up and carrying fuel particles discharged through the openings into the downdraft in said duct, and an upwardly opening slit in the back of said elbow for by-passing part of the air traversing said duct into the elbow, said slit having spaced front and rear walls for guiding and directing by-passed air downwardly into the elbow and terminating behind said discharge opening, whereby the by-passed air sweeps over the bottom of the elbow and prevents fuel particles from accumulating thereon and whereby outside air flowing past the outlet of the nozzle has an induction effect tending to draw fuel from the nozzle.

8. A delivery system for powdered fuels comprising a storage receptacle for powdered fuel having a bottom therein, a vertical discharge duct at the end of said receptacle extending downwardly from said bottom and provided at the lower end thereof with a horizontal extension, a longitudinal trough in said bottom opening into said duct, a longitudinal passage below said trough opening at one end into said duct, and openings interconnecting the trough and said passage through which fuel passes from the trough into the passage, screw conveyer means in said trough for moving fuel into said duct and for agitating fuel in the trough to promote flow of fuel through said openings into said passage, a pipe in and of smaller diameter than the duct for receiving fuel delivered to the duct by said conveyer, said pipe extending downwardly to substantially the bottom of the duct, an elbow on the lower end of the pipe having a discharge opening arranged to deliver fuel substantially horizontally into the extension of said duct, means for forcing a current of air under pressure downwardly through the duct around said pipe and past the discharge opening of said elbow, nozzles extending into said passage from said openings, said nozzles having outlets facing the discharge duct and adapted to deliver fuel from the openings horizontally into the passage, and means for creating a forced draft of air longitudinally in said passage and in the direction of said duct whereby said air flowing past the outlets of said nozzles has an induction effect tending to draw fuel from the nozzles and whereby fuel discharged from the nozzles is moved into the duct by said forced draft of air, and an upwardly opening slit in the back of said elbow for by-passing part of the air traversing said duct into the elbow, said slit having spaced front and rear walls for guiding and directing by-passed air downwardly into the elbow and terminating behind said discharge opening, whereby the by-passed air sweeps over the bottom of the elbow and prevents fuel particles from accumulating thereon and whereby outside air flowing past the outlet of the nozzle has an induction effect tending to draw fuel from the nozzle.

9. A delivery system for powdered fuels comprising a storage receptacle for powdered fuel having a bottom therein, a vertical discharge duct at the end of said receptacle extending downwardly from said bottom and provided at the lower end thereof with a horizontal extension, a longitudinal trough in said bottom opening into said duct, screw conveyer means in said trough for moving said fuel into said duct, a pipe in and of smaller diameter than the duct for receiving fuel delivered to the duct by said con-

veyor means, said pipe extending downwardly to substantially the bottom of the duct, an elbow on the lower end of the pipe having a discharge opening arranged to deliver fuel substantially horizontally into the extension of said duct, means for forcing a current of air under pressure downwardly through the duct around said pipe and past the discharge opening of said elbow, an upwardly opening transversely elongated slit in the back of said elbow for by-passing part of said air into the elbow, said slit having spaced walls for guiding and directing by-passed air downwardly into the elbow and terminating behind said discharge opening whereby the by-passed air sweeps over the bottom of the elbow and prevents fuel particles from accumulating thereon, and whereby outside air flowing past the outlet of the nozzle has an induction effect tending to draw fuel from the nozzle, a longitudinal passage below said trough opening at one end thereof into the annular space between said duct and said pipe, openings in the bottom of the trough through which fuel passes into the passage, nozzles extending into said passage from said openings, said nozzles having outlets facing the discharge duct and adapted to deliver fuel from said openings horizontally into said passage, jackets around and spaced from said nozzles, and means for delivering air under pressure to each of said jackets behind the outlets of said nozzles, whereby said jackets initially confine the air to increase its velocity and directs such air past said outlets so that the air has an induction effect tending to draw fuel from the nozzles and whereby fuel discharged from the nozzles is carried along suspended in the air to said duct.

10. A delivery system for powdered fuels comprising a storage receptacle for powdered fuel having a bottom therein, a vertical discharge duct at the end of said receptacle extending downwardly from said bottom and provided at the lower end thereof with a horizontal extension, a longitudinal trough in said bottom opening into said duct, screw conveyer means in said trough for moving said fuel into said duct, a pipe in and of smaller diameter than the duct for receiving fuel delivered to the duct by said

conveyer means, said pipe extending downwardly to substantially the bottom of the duct, an elbow on the lower end of the pipe having a discharge opening arranged to deliver fuel substantially horizontally into the extension of said duct, means for forcing a current of air under pressure downwardly through the duct around said pipe and past the discharge opening of said elbow, an upwardly opening transversely elongated slit in the back of said elbow for by-passing part of said air into the elbow, said slit having spaced walls for guiding and directing by-passed air downwardly into the elbow and terminating behind said discharge opening whereby the by-passed air sweeps over the bottom of the elbow and prevents fuel particles from accumulating thereon, and whereby outside air flowing past the outlet of the nozzle has an induction effect tending to draw fuel from the nozzle, a longitudinal passage below said trough opening at one end thereof into the annular space between said duct and said pipe, openings in the bottom of the trough through which fuel passes into the passage, nozzles extending into said passage from said openings, said nozzles having outlets facing the discharge duct and adapted to deliver fuel from said openings horizontally into said passage, jackets around and spaced from said nozzles, and means for delivering air under pressure to said passage, said means having a plurality of branch outlets extending into said passage and connecting with respective jackets behind the outlets of said nozzles, whereby said jackets direct air past said outlets so that the air has an induction effect tending to draw fuel from the nozzles and whereby the fuel-laden air is directed by the jackets to said duct.
